(57) **CLAIM**

The ornamental design for a hinged container, as shown and described.

DESCRIPTION

FIG. 1 is a top, front perspective view of the hinged container showing the new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof; and,

FIG. 7 is a left side elevation view thereof.

The broken line portions of FIG. 3 are included for the purpose of illustrating unclaimed structure and form no part of the claimed design.
